CLAIM

The ornamental design for a bag, as shown and described.

DESCRIPTION

1. Bag

1.1 : Front

1.2 : Front

1.3 : Back

1.4 : Right

1.5 : Left

1.6 : Bottom

1.7 : Top

1.8 : Perspective

The design is a bucket bag, medium size, with a drawstring sliding system at the top in order to be able to close the bag; it has a long adjustable shoulder strap mix leather and chain and a removable leather handle, with the letters "lancel" stitched in the leather and metal hook on both sides; it has four metal feet at the bottom base in order to protect the bag when put on the floor; inside multiple pockets: zip pocket and two open flat pockets to put cell phone and other customers' essentials.
